MESNE ASSIGNMENTS, TO SEMET-SOLVAY ENGINEERING CORPORATION, OF NEW
YORK, N. Y., A CORPORATION OF NEW YORK

GAS MANUFACTURE

Application filed September 15, 1924. Serial No. 737,656.

It is the customary practice in the manufacture of water gas to use a plant consisting of a generator, carburetor and super-heater, together with a wash box or seal, through which the gas from the plant passes and which prevents the return of the gases once they have passed therethrough.

Until recent years, it has been the practice to pass steam directly into the generator at either the bottom or the top thereof when making gas, the former instance being called an "uprun" and the latter a "downrun". It has recently become customary in many plants, however, to pass steam directly into the super-heater in order to make what is called a "backrun". It is to this latter type of plant that our invention is directed.

Our construction embodies primarily the positioning of a single swinging valve between the port leading from the superheater to the wash box and the port leading from the generator to the wash box, so that either of these ports may be closed by the simple movement of this single valve at the same time the other port is opened. Our construction, furthermore, utilizes a swinging valve operated by the same means which operate the first mentioned valve, for directing the passage of steam either through the superheater or through the generator. And, further, the blower pipe passageway to the gas plant generator is at certain times utilized as a passageway for steam into the generator, as well as a passageway for gas from the generator.

Among the objects of our invention, therefore, are the provision of a single valve which may be more quickly reversed than two independent valves, with the consequent reduction in cost because of the smaller number of valves used, as well as reduction of time required to open and close the valves; the constant closing of the "backrun" line except during that portion of the cycle when "backrun" gas is being made with the consequent prevention of hydrocarbon vapors backing up into the "backrun" line, condensing out and filling the "backrun" pipe with a tarry or pitchy deposit; the elimination of the possibility of one valve stricking or failing to

work while another is open; the positive assurance that steam will be directed through the port through which it is intended to be directed because of the connection of the steam valve with the main valve; the reduction in the amount of steam pipe used; the provision of an open passage through the superheater offtake to the superheater stack cap so as to eliminate any possibility of an explosion during the blowing period because of blowing air directly into the holder; the locating of the main valve directly over the wash box and the supplying of water leading to the wash box over the valve constantly so as to keep it clean; and the positive closing off of the superheater offtake with the wash box so as to prevent passage of steam to the wash box during the "backrun" operation.

With these, and other objects in view, our invention consists of the arrangement, combination and construction of the various parts of our improved system as described in the specification claimed in our claims and shown in the accompanying drawing, in which:

Fig. 1 is a side elevation of a gas plant embodied in our invention.

Fig. 2 is a plan view of the same.

Fig. 3 is a detail view, in elevation and partly in section, of the main double acting valve utilized in our invention.

Fig. 4 is a section through the valve housing showing said valve approximately from the center thereof.

We have shown a gas plant consisting of a water gas generator 5, a carburetor 6, a superheater 7, and a wash box 8. The customary fuel opening 9 for the generator, oil spray opening 10 for the carburetor, and stack cap 11 for the superheater are shown more or less diagrammatically, inasmuch as they form no part of our invention.

Suitable connections for the various elements are provided as in the conduit 12 leading from the generator to the carburetor, the conduit 13 leading from the carburetor to the superheater and the offtake conduit 14 leading from the superheater through the valve housing 15 into the wash box 8. A gas offtake passage 16 leads from the wash box 8 to a gas holder. A passage 17 leads

from the housing 15 through the passage 18 into the bottom of the generator.

Suitably positioned in the housing 15 is a shaft 19, on which is secured a yoke 20 having a flared and rounded seat 21 at approximately the crest of the yoke. A bolt 22 extends through this seat having the head thereof bearing against the inner face of the yoke.

- 10 A pair of separated plates 23 joined together at approximately their centers by a web having a rounded portion 24, are secured to the yoke 20 by reason of the bolt 22 extending through the rounded portion 24, so as
15 to cause one portion thereof to bear in the seat 21 and the other portion thereof to bear in a seat 25 provided on the end of the bolt 22 and secured in place by the nut 26 on the end of the bolt.

20 One end of the shaft 19 is provided with a lever 28 connected with a shaft 29. Arms 30 connect the shaft 29 with a hydraulic piston contained in the cylinder 31.

It will be noted that the aperture through the portion 24 is of larger diameter at the outer edges thereof than at the center so that the bolt 22 bears against the sides of the aperture at substantially one point only, thus permitting universal movement of the portion 24 and likewise the plates 23. The shank of the bolt 22, between the head thereof and the portion 24, is of smaller diameter than the remainder of the shank so as to provide a shoulder on the bolt bearing against the seat 21 to prevent tightening of the nut 26 to such a degree as to prevent universal movement of the portion 24. The shaft 19 is so positioned in the housing 15 that when it is rotated in one direction, one of the plates 23 will engage the mouth of the vertical portion of the passageway 14 while when the shaft is moved in the opposite direction the other plate 23 will engage the face of the horizontal portion of the passage 17.

45 For the introduction of steam into the system, we utilize a passage 32, which communicates with the passages 33 and 34, the passage 33 leading into the passage 14 and the passage 34 leading into the passage 17. A double acting valve is positioned at the junctures of the passages 32, 33 and 34 as at 35, and the operation thereof is controlled by means of a lever 36 attached to the end of the shaft 29.

55 Positioned in the housing 15 is a ring 37 connected by the passageway 38 with a suitable source of water supply. The ring 37 is perforated and a constant supply of water is carried therethrough with the result that the plates 23 are constantly being supplied with water so as to prevent the collection of foreign matter thereon. The excess water drips from the plates 23 down into the wash box 8 so as to constantly maintain a sufficient supply of water therein.

65 The passage 39 is utilized for air blasting,

being connected with the generator 5 through the passage 18. When the blasting is discontinued, the valve 40 is closed so as to permit the use of the passage 18 for other purposes.

It will thus be seen that in making an "up-run", steam is passed through the passages 32, 34 17 and 18 into the bottom of the generator and gases are carried from the top of the generator through the passage 12 into the carburetor 6, through the passage 13, into the superheater 7, through the offtake 14 and the housing 15 into the wash box 8. During this operation the plates 23 are in such position as to close the housing 15 to the passage 17, as shown in Fig. 1. 70 75 80

In making a "backrun" the hydraulic cylinder 31 is operated so as to reverse the plates 23 and close the passage between the housing 15 and the passage 14, at the same time closing, through the valve 35, communication between the passage 32 and 34 and permitting steam entering the passage 32 to be directed through the passage 33 into the off-take 14 from whence it follows through the superheater 7, the passage 13, the carburetor 6, the passage 12 and the generator 5 into the passage 18 and thence through the passage 17 into the housing 15 and the wash box 8. It will be noted that the passage 18 bypasses the carburetor and superheater, that is to say the passage 18 does not pass through the carburetor and superheater but conducts the backrun water gas from the generator directly to the wash box.

It will be noted that with the foregoing construction all of the objects mentioned are accomplished and a highly efficient gas plant provided. 100

It is obvious that various changes may be made in the arrangement, combination and construction of the various parts of our improved device without departing from the spirit of our invention, and it is our intention to cover by our claims such changes as may be reasonably included within the scope thereof.

What we claim is:

1. A water gas plant including a single generator and a single superheater, a gas line leading from said generator and bypassing the superheater, a gas line leading from said superheater, a housing into which both of said lines extend, a washbox communicating with said housing, and valve mechanism in said housing adapted to alternately open one of said lines and close the other. 115

2. A carburetted water gas set comprising a single generator, a single carburetor, and a single superheater, the individual units being located in separate and detached shells, a gas line leading directly from said generator and bypassing the carburetor and superheater, a second gas line leading directly from said superheater, a housing into which 120 125 130

both of said lines extend, a washbox communicating with said housing, and valve mechanism in said housing adapted to alternately open one of said lines and substantially simultaneously close the other.

3. A water gas plant, including a single generator, and a single superheater, a gas line leading from said generator, and bypassing the superheater, a gas line leading from said superheater, a housing into which both of said lines extend, and a swinging valve in said housing adapted to alternately open one of said lines and close the other.

4. A water gas plant, including a single generator, and a single superheater, gas outlet lines leading from both said generator and said superheater, said line from the generator by-passing the superheater, a common housing into which said lines lead, a steam line leading into both said gas outlet lines, a valve in said steam line adapted to alternately permit the passage of steam into one of said gas outlet lines and prevent passage of steam into the other, and a valve in said housing between the ends of the outlets of said gas outlet lines adapted to alternately open one and close the other of them.

5. A water gas plant, including a single generator, and a single superheater, gas outlet lines leading from both said generator and said superheater, said line from the generator by-passing the superheater, a common housing into which said lines lead, a steam line leading into both said gas outlet lines, a valve in said steam line adapted to alternately permit the passage of steam into one of said gas outlet lines and prevent passage of steam into the other and a valve between the ends of said gas outlet lines adapted to alternately open one and close the other of them, and common actuating means for both said valves.

6. A water gas plant, including a single generator, a single superheater and a wash box, a gas outlet line leading from said generator to said wash box, and a gas outlet line leading from said superheater to said wash box, and by-passing the superheater, and means operated from a single source of power for alternately opening one of said lines and closing the other, said means consisting of a swinging valve positioned adjacent the wash box, and means for supplying water to said wash box, including a spray adapted to dispose said water over said valve.

JOHN B. EBERLEIN.
